UNITED STATES PATENT OFFICE.

JACOB HENRY HARD, OF OSMOND, NEBRASKA.

TIRE-DEFLATING CAP.

1,076,981.

Specification of Letters Patent. Patented Oct. 28, 1913.

Application filed April 3, 1912. Serial No. 688,194.

To all whom it may concern:

Be it known that I, JACOB HENRY HARD, a citizen of the United States, and a resident of Osmond, in the county of Pierce and State of Nebraska, have invented a new and Improved Tire-Deflating Cap, of which the following is a specification:

My invention is an improvement in tire inflating valves, and has for its object the provision of two caps, one of which is provided with an internally threaded end of the same diameter as the cap, and the other cap is externally threaded for engaging either the ring or the cap, and both caps are provided with pins extending centrally from the inclosed end of the caps, and the pin of the inner cap is provided with a transverse notch.

In the drawings:—Figure 1 is a side view 20 of the improvement; Fig. 2 is a vertical section; Fig. 3 is a side view showing the parts reversed; and Fig. 4 is a bottom plan view of Fig. 3.

In the present embodiment of the invention, a tube 1 is provided, having at its center a diaphragm 2. The tube is internally threaded on one side of the diaphragm, as indicated at 3, and is reduced externally at the said end, as indicated at 4, and an annular shoulder 5 is formed between the reduced portion and the main portion. The opposite end of the tube is reduced in diameter by offsetting the end of the tube inwardly, as indicated at 6, and an annular series of openings 7 is provided in the wall of the tube between the diaphragm and the inwardly offset portion. The offset portion 6 is threaded internally, as shown at 8 and externally as shown at 9. A pin 11 extends axially of the tube from the center of the diaphragm toward the offset end, and a packing plate 12 is arranged on the opposite face of the diaphragm. A second tube is composed of two portions 13 and 14 of unequal diameter connected by a tapering portion 15. The portion 14 is externally threaded at 16, and an annular radial rib 18 extends from the inner end of the portion 14 at the junction of the portions 14 and 15. The rib is adapted for engagement by the end of the offset portion of the tube, and the said rib is provided with a lateral flange 19, extending parallel with the surface of the tube, and extending over the end of the offset portion of the tube, when the end of the

said portion engages the rib. The outer end of the portion 13 is longitudinally slotted or notched at 20. The internal diameter of the portion 6 of the tube 1 is the same as that of portion 4 of the other tube and the portion 14 will fit in either end of the tube 1. The device presents in fact two tubes so arranged that either end of one will screw upon a valve stem, one end protecting the valve in the usual manner, and the other end opening the valve by means of its pin for the escape of air, and so arranged that one end of the smaller will screw into either end of the larger tube where it may be carried in order to be used as a wrench for the removal of the valve core.

The offset portion 6, when the parts are in the position of Figs. 1 and 2, engages outside of the portion 14 of the tube 13—14, to assist in holding the parts in their position and to prevent the easy disengagement of the tube 13—14 from the cap 4. The portion 13—14 of the device has a double engagement with the deflating cap, since the portion 14 screws into the portion 6 and the portion 19 fits outside of the said portion. The flange 19 is made short, so that the greater part of the thread of the portion 14 will be exposed, a portion sufficient to enter the portion 4 of the other section. When using the device as a deflator, the tube 13—14, which is merely the wrench for removing the valve from the valve stem, might be slightly set in, and the said tube might be lost while the device is being used to deflate.

I claim:

As an article of manufacture, a deflating device comprising a cap and an integral coaxial ring, said cap being internally threaded and the ring being internally and externally threaded and of the same internal diameter as the cap, the cap having a pin coaxial with the ring, and a second cap externally threaded for engaging within the first-named cap or within the ring, said second cap having a tubular stem provided with a transverse notch at its free end and having a radially outwardly offset flange for engaging outside of the outer threaded surface of the ring, for the purpose specified.

JACOB HENRY HARD.
